UNITED STATES PATENT OFFICE.

RAY L. CARTER, OF PHOENIX, NEW YORK.

DOVETAILING MECHANISM.

Application filed November 8, 1926. Serial No. 147,030.

This invention relates to a templet for guiding routing and other tools when cutting dovetails, and has for its primary object to provide a pattern or templet, by which the flaring tenons and the correspondingly shaped mortises of side and end sections of boxes, drawers, and the like, may be simultaneously cut by the routing bit. A further object is to provide a novel angular support for the templet and the work, the said support comprising a plane horizontal table and an integral apron, the said parts being equipped with similar independent clamps, by which the two box sections may be rigidly held at right-angles to each other while the routing bit traces the dovetail pattern and effects the rapid and accurate cutting of the interlocking tongues and sockets of the two sections at a single operation. A further object is to provide gaging means for positioning the two sections in staggered relation to each other for enabling the tool to properly cut dovetail tenons at the end of one piece of wood, and by the same operation cut corresponding mortises in the end of a like piece of wood without necessitating readjustment of the device or disturbing of the work. A further object is to provide tension means for normally spacing the clamping members from the table and apron. And a further object is to provide means for clamping the device to a bench or other support.

The various features and parts of the invention will be understood from the detailed description which follows, and by reference to the accompanying drawings in which—

Figure 1 is a top plan view of the complete device, showing the side and end pieces of the work in the operative position, also showing the said pieces operated upon. Fig. 2 is a front side elevation of the same. Fig. 3 is an end elevation showing router cutting dovetails. Fig. 4 is an edge view, showing the box-sections interlocked. Fig. 5 is a top plan view of same. Fig. 6 is a view of the sections of box ready to be assembled. Fig. 7 is a similar view of the sections when taken from the machine. Fig. 8 is a plan view of the templet. Fig. 9 is respectively a side elevation and bottom end view of the dovetailing bit.

In the drawings, 2 represents an angular

frame or body, comprising a relatively large 55 rectangular horizontal portion 2', and an integral vertical portion 2^a. The portion 2^a is preferably formed with a rearwardly extending arm 2^b, (see Fig. 3), which is perforated and threaded to receive a screw 3, by which the body may be rigidly clamped to a bench or other support, as 3'. 4—4' represent similar elongated work-clamping members having perforated end portions 4^a—4^b, which loosely receive clamping screws 5—5', 60 the latter being screwed respectively into threaded sockets 2^c—2^d, of the table 2' and the apron 2^a, and the free ends of said screws being formed with hand-knobs 5^a—5^b, by which the screws are manipulated. The 70 screws 5—5' are preferably fitted with similar coil compression springs 6, whose tension normally tends to suitably space the clamps from the table and apron for facilitating applying and removing the work, when the screws are loosened, as shown in Figs. 1, 2 and 3. The apron 2^a is preferably disposed exactly at right-angles to the table 2'. The clamps 4 and 4' are provided respectively 75 for rigidly clamping and holding a side section or portion, as A, and an end section, as B, of a box or like part, perpendicular to each other, while a routing tool, as 10, cuts the interlocking tenons and mortises, for effecting the ordinary dovetail corner joint, 80 when the said sections are assembled (see Figs. 4 and 5). The sections A and B are preferably the same breadth and thickness and the said sections are applied to the frame 2, in advance of the dovetailing work, in such 90 manner that their corresponding ends, as a and b, are disposed adjacent the angle x of the frame (see Figs. 1, 2 and 3). The end a of section A is preferably disposed flush with the outer face x' of the apron 2^a, while 95 end b of the section B is arranged to overlap the end a and is disposed flush with the top surface of the section A. In the preferred arrangement, the two sections are staggered or offset slightly, as best seen in Figs. 1 and 100 2, wherein the left edge of section A, and the right edge of section B project beyond the corresponding edges of the opposing sections (see Figs. 1 and 2). This offsetting of the sections is effected by means of similar gages 105 or guides a' and b', which are respectively mounted upon the table 2' and the apron 2^a and held in place by screws 2^c. This off-

setting of the sections preferably amounts to substantially one-half the distance between the centers of adjacent tongues and mortises of the dovetails.

5 The dovetail templet, indicated at 9, comprises a relatively stiff plane sheet of fiber or metal, preferably rectangular in shape, whose opposite ends are notched, as shown at 9^a, in Figs. 3 and 8, to loosely receive the 10 screws 5. The templet 9 is preferably rigidly secured to the underside of the clamp 4, by screws 9^b, and thence extends forwardly and overhangs the outer face ^{a'} of the apron 2^a. This forward edge of the templet 15 is formed with a number of serrations or fingers 9', the said fingers all being the same length and breadth, and being spaced equidistantly from center to center, and the length of said fingers preferably substantially 20 equals the combined length of the alining mortises 7 and the tenons 8 of the sections A and B (see Fig. 1). The free ends of the fingers 9', are preferably round corresponding to the shape of the tenons 8, and 25 the said fingers are slightly narrower than the flared tops of said tenons, as shown in Figs. 1 and 2. The cutting of the dovetails may be effected by means of an ordinary motor driven router, one of which is illustrated conventionally at 12, in Fig. 3, wherein the rotary conical bit 10 is shown in the act of forming one of the round undercut tenons 8 of the section B. During the dovetailing the router 12 preferably rests upon 30 and is moved frictionally over the templet 9. The tool 10 has its cutting end fluted or cut away at 10', (see Figs. 3 and 9), for providing oppositely facing angular spurs or blades 10^a, the sharp edges 10^b of which taper for cutting the bevels of the tenons and 35 grooves of the dovetails. The shank 10^c of the tool 10 passes loosely through a guide 13, that comprises the lower end of an inverted conical cap 13', which forms a part of the 40 motor casing 13^a and is nonrevolute. The guide 13 is usually cylindrical, and is preferably substantially the same diameter as the breadth of the fingers 9' and the spaces or bights 9^c between the said fingers. During 45 the dovetailing the guide 13 traverses frictionally the relatively narrow serrated edges of the templet 9, and enables the bit to cut the tenons 8 and the mortises 7 exactly alike as to size and shape, as best seen in Figs. 5, 6 50 and 7. The guide 13 is of greater diameter than the narrow end of the bit 10. This effects the broadening of the tops of the tenons 8 and the corresponding narrowing of the tops of the mortises relatively to the 55 tongues 9' and the bights 9^c, as shown in Figs. 1 and 2, and prevents the bit from injuring the templet. The bit 10 is driven directly by the armature shaft of the motor 14, and is usually detachably connected to said shaft 60 by means of any suitable chuck, as 14' (see 65

Fig. 3). The encased motor 14 is adjustable axially in a base 15 that rides upon the templet and disposes the tool 10 for cutting in the proper plane below the base. The arrangement of the templet 9 and the peculiar disposition of the sections A and B, are such that the bit 10 alternately cuts the tenons 8 and the mortises 7. When the sections are removed from the machine both must be reversed as may be understood by comparing Fig. 7 with Fig. 6, in order to properly fit the tenons into the sockets, as shown in Figs. 4 and 5. By providing the templet 9, and mounting it rigidly beneath the clamp 4, the said templet may be raised and lowered by simply loosening or tightening the screws 5, for accommodating box or other sections A of different thicknesses. Except for the matter of the adjustments last above referred to, the device when constructed as herein shown, is always ready for instant use, and owing to its peculiar construction and arrangement, the dovetailing may be effected rapidly, accurately and economically, by persons of ordinary skill, and when the sections A and B are properly prepared they may be placed in the machine and clamped in place in less than a minute, and the dovetailing of the corresponding ends of the opposing sections, even when the sections are relatively broad, may be accurately wrought in two or three minutes time. The cutting of the tenons and mortises of two sections simultaneously by the same tool not only saves considerable time and labor, but also ensures the 100 perfect interfitting of the dovetailed parts, as shown in Figs. 4 and 5.

Having thus described my invention, what I claim, is—

1. A dovetail mechanism including a horizontal table and a vertical apron adapted to seat adjacent sections of a box or the like, and similar means for clamping the said sections to the table and apron, gaging means for staggering said sections, a templet overlying the section carried by the said table, its forward margin being formed with spaced fingers, and said fingers overlying the top end of the section carried by the apron, and a router adapted to be moved over the top face of said templet including a rotary conical bit adapted to cut tenons and mortises in the corresponding ends of said sections below the plane of the templet, said bit having a guide portion that traverses the edges 115 of the fingers.

2. A dovetailing mechanism, including an angular frame consisting of a horizontal table and a vertical apron, means for clamping sections of a box or the like against the top face of the table and the outer face of the apron, a templet overlying the section carried by the table having one edge formed with spaced fingers that overlap the top end 125 of the section carried by the apron, means 130

for staggering the said sections, a motor supported by a base adapted to be moved over the top surface of the templet, and a bit driven by the motor, said bit being arranged to simultaneously cut tenons and mortises in the corresponding ends of said sections below said templet, said bit being formed with a guide that traverses the edges of said fingers.

10 3. In a dovetailing mechanism, a frame including a horizontal seat and a vertical seat adapted to support respectively a side and an end section of a box or the like at right angles to each other, the corresponding ends of said sections overlapping and the top end of the vertical section being disposed flush with the top surface of the horizontal section, a plane templet overlying the horizontal section, its forward edge being formed with spaced fingers, said fingers overlapping and engaging the adjacent end of the vertical section, a routing machine adapted to be moved over said templet comprising a motor-driven bit that projects below the templet, said bit having a guide portion that traverses the facing edges of the fingers while the tool cuts tenons in the end of the

vertical section, and by the same operation cuts correspondingly shaped mortises in the overlapped end of the horizontal section.

30

4. In a dovetailing mechanism, the combination with a frame comprising a horizontal seat and a vertical seat adapted to support respectively sections of a box or the like, and clamping means for rigidly holding the sections against said seats, of a templet interposed between the horizontal seat and its clamping member and overlying the top face of the side section, said templet being formed with spaced fingers that project beyond the face of the vertical seat and overlap the corresponding ends of said sections, a router adapted to be moved over the top face of the templet including a rotatable bit and a guide adapted to traverse the lateral edges of the fingers for guiding the bit while the latter cuts dovetail tenons and sockets in the adjacent ends of said sections simultaneously, and gaging means for staggering the said sections.

40

45 In testimony whereof I affix my signature.
